TRUCK MIRROR

Hugo Magi, Etobicoke, Ontario, Canada, assignor to Dominion Auto Accessories Limited, Toronto, Ontario,
Canada

Filed Sept. 24, 1969, Ser. No. 19,287

Term of patent 14 years

Int. Cl. D12—14

U.S. Cl. D14—6

FIG. 1

FIG. 2

FIG. 1 is a perspective view showing my new design for a truck mirror, taken from in front;

FIG. 2 is a perspective view of the truck mirror of FIG. 1, taken from behind; and

FIG. 3 is an end view of the truck mirror of FIG. 1.

I claim:

The ornamental design for a truck mirror, as shown.
